MOUNTING MEANS FOR PUMP IMPELLERS
AND THE LIKEClark D. Bower, Pomona, Calif., assignor, by
mesne assignments, to Fairbanks, Morse & Co.,
a corporation of Illinois

Application August 1, 1944, Serial No. 547,616

6 Claims. (Cl. 287—52.05)

My present invention relates to a shaft and hub mounting means for rotary elements, and more particularly to an improved means for adjustably and firmly securing the impeller of a centrifugal type pump upon a driving shaft.

An object of the invention is to provide a simple, practical and effective means for securing a hub supported element of a rotary machine upon a driving shaft.

Another object of the invention is to provide an improvement in the manner of adjustably mounting the rotary impellers of a centrifugal type pump in an operative position upon a driving shaft.

Another object of the invention is to provide a positively acting means for adjusting and positioning a number of impellers or propellers of a centrifugal pump upon a driving shaft in such a manner that the impellers may be spaced in proper clearance relation with adjacent cooperating parts when in operation.

It has heretofore been common practice in the construction of centrifugal pumps, and more especially in the vertical turbine and impeller types having multiple stages, to fasten or position each of the impellers by means of a split bushing that is adapted to receive a nut which serves to move the impeller along the outside tapered surface of the bushing to thereby tighten the bushing upon the shaft and grip the shaft and thus produce a frictional driving connection between the shaft, the bushing and the impeller. With this prior arrangement it will be obvious that the amount of torque that can be transmitted from the shaft to the impeller will be dependent not only upon the amount of contact between the parts, but also upon the character of the contact surfaces between the several parts. In most pumps of this type it is also important that the axial position of the impeller upon its driving shaft be rigidly maintained with reference to the fluid directing shroud or bowl with which the impeller is associated. For example, in centrifugal pumps of the impeller type having impellers of the semi-open type that rotate in close proximity to stationary parts, the clearances must necessarily be very small. It is, therefore, a further object of my invention to provide a means which will establish a firm driving connection between the impellers and the shaft and also permit of a close adjustment in the positions of the impellers with respect to each other and thus meet the above requirements in a novel and efficient manner.

Other objects and advantages of the invention will be in part evident to those skilled in the

art, and in part pointed out hereinafter in the following description taken in connection with the accompanying drawings, wherein there is shown by way of illustration and not of limitation preferred embodiments thereof.

In the drawings:

Figure 1 is a vertical sectional view showing the invention as applied to the shaft and impellers of a multiple stage impeller-type pump.

Figure 2 is a fragmentary sectional view showing the details of the invention as illustrated in Figure 1, and

Figures 3 and 4 are fragmentary plan views of the device, looking down along line A—A of Figure 2, and respectively showing the device as provided for operation by an open-end or spanner type wrench.

In the drawings the invention is shown, for the purpose of illustration, as applied to a multiple stage submersible pump of the type employing a plurality of impellers that are adapted to be rotated at high speed within a suitable fluid directing housing. As shown in Figure 1, such a pump in the main comprises a driving shaft 10 that is adapted to be driven by a motor (not shown) which is generally located at the top of a well or the like. In this instance the shaft 10 carries two impellers 11 and 12 that are secured thereupon in accordance with a preferred embodiment of the present invention. In this arrangement the shaft 10 will be journaled and supported at its upper end by means of a suitable step bearing that will prevent any axial movement thereof and, at the points where the impellers 11 and 12 are mounted, the shaft 10 will extend through suitable water lubricated and resilient guide bearings 13, 14 and 15 which may be of rubber or other type of yielding plastic material.

The upper one of these guide bearings 13 is carried by an inner portion of a fluid directing bowl or shroud 16 that is adapted to be secured upon the lower end of a discharge pipe 17 which leads from the pump. The bowl or shroud 16 is also shown as provided with a plurality of fluid directing channels or conduits 18 through which the fluid may flow upwardly from the impeller 11. At its lower end the fluid directing bowl or shroud 16 supports a second somewhat similar bowl or shroud 19 in which the guide bearing 14 is mounted. This bowl or shroud 19 is also provided with fluid directing channels or conduits 20 that serve to direct the fluid discharged by the impeller 12 to a point below the impeller 11. Mounted below and secured to the bowl or shroud 19 there is an additional fluid directing shroud 21 that carries

50

the guide bearing 15 and also provides a plurality of radially spaced channels or conduits 22 through which the fluid is directed from an intake pipe 23 to a point immediately below the impeller 12. With this arrangement it will be seen that when the impellers 11 and 12 are rotated at high speed, they will operate in their respective zones to centrifugally impart movement to a fluid as it passes through the conduits 18, 20 and 22. For efficient operation, it will be understood that the position of the impellers 11 and 12, with respect to the adjacent lands or channel forming surfaces 24 and 25 of the members 19 and 21, adjacent which they operate, must be closely maintained. Therefore, in a pump of this type it is desirable to provide a means by which the impellers 11 and 12 may be adjusted along the shaft 10 and with respect to the cooperating stationary parts of the pump housing. At the same time, this means must operate to firmly secure the impeller or rotary element against any radial or axial displacement after these adjustments have been made.

As is more clearly shown in Figure 2 of the drawings, the invention, in its preferred form, contemplates the provision of an undercut portion or groove 26 upon the shaft 10 at a point adjacent where an impeller 11 or 12 is to be mounted. In this arrangement a groove or undercut portion 26 provides what may be termed two oppositely arranged and spaced shoulders 27 and 28 between which a mutilated nut or split collar 29 may be positioned in a tight fitting, but turnable manner. Cooperating with the mutilated nut or split collar 29 the impeller is provided with an internally threaded and extending hub portion 30 that is adapted to overlap the mutilated nut or split collar 29 and thus retain it between the spaced shoulders 27 and 28 formed upon the shaft 10. At its other end the impeller has a hub portion 31 that is adapted to provide a relatively tight sliding fit upon the shaft 10 at one side of the undercut portion 26, and cooperating with this portion of the hub, the shaft 10 is preferably provided with one or more Woodruff type of key 32 that engages a keyway 33 formed in the hub portion 31 of the impeller. With the impeller mounted in this manner it will be seen that by turning the mutilated nut or split collar 29 about the shaft 10, it will be possible, because of the external threads thereupon and the internal threads carried by the extending hub portion 30 of the impeller, to move the impeller axially of the shaft in either direction from any given point after the parts have been assembled as shown, and in this way any desired clearance may be established between blades 34 of the impeller and the stationary lands or surfaces 24 or 25 of the pump housing. For the purpose of securing the impellers against any inadvertent or accidental displacement along the shaft 10, the invention also contemplates the utilization of a ring or nut 35 that is adapted to be threaded upon the extending threaded portion of the mutilated nut or split collar 29 and which, when tightened, will operate to lock the parts securely together and thus permanently fix the impeller upon the shaft 10 after the desired adjustment has been made.

In order that the mutilated nut or split collar 29 and the locking nut 35 may be conveniently turned, as in making the above described adjustment, it is contemplated that these members may be provided with hexagonally arranged surfaces 36 and 37, as shown in Figure 3 of the drawings, or they may be made of a type as shown at

29' and 35' suitable for turning with a conventional spanner wrench by the provision of suitable spaced notches 38 and 39 in the outer perimeters thereof, as shown in Figure 4 of the drawings.

While I have, for the sake of clearness and in order to disclose the invention so that the same can be readily understood, described and illustrated specific devices and arrangements, I desire to have it understood that the invention is not limited to the specific means disclosed, but may be embodied in other ways that will suggest themselves to persons skilled in the art. It is believed that this invention is new and it is desired to claim it so that all such changes as come within the scope of the appended claims are to be considered as part of this invention.

Having thus described my invention, what I claim and desired to secure by Letters Patent is:

1. In a shaft and hub securing means of the character described, the combination of a shaft having spaced shoulders formed thereupon, a split externally threaded collar disposed between the shoulders upon said shaft, a hub carrying member having an internally threaded portion at one end adapted to extend over said split collar and another portion adapted to slidably engage said shaft, a keying means between the latter portion of said hub carrying member and said shaft, and means carried by said split collar and engaging the end of said hub carrying member for locking said parts in an operative position.
2. In a shaft and hub securing means of the character described, the combination of a shaft having spaced shoulders formed thereupon, a plurality of externally threaded collar forming members disposed around said shaft between said shoulders, a hub carrying member having an internally threaded portion at one end adapted to extend over said plurality of externally threaded collar forming members and another portion slidably engaging said shaft, a keying means between the latter portion of said hub carrying member and said shaft, whereby said hub carrying member may be adjusted axially along the shaft by a turning of said plurality of externally threaded collar forming members about the shaft.
3. In a shaft and hub securing means of the character described, the combination of a shaft having a groove extending therearound, a split externally threaded collar disposed in said groove and extending around said shaft, a hub carrying member having an internally threaded portion at one end adapted to extend over said externally threaded split collar and another portion slidably engaging said shaft, a keying means between said latter portion and said shaft, whereby said hub carrying member may be adjusted axially along the shaft by a turning of said split collar within the internally threaded and extending end of said hub carrying member, and means carried by said split collar and engaging the end of said hub carrying member for locking said parts in a fixed position.
4. In an impeller supporting shaft, the combination of a driving shaft having a groove formed thereabout at a point corresponding to the location of an impeller to be mounted thereupon, an externally threaded split nut disposed in the groove of said shaft, an impeller slidably mounted upon said shaft and having an internally threaded overhanging portion into which said split nut may turn, a keying means between said shaft and said impeller, whereby said impeller may be adjusted axially along the shaft with re-

spect to said groove by a turning of said externally threaded nut about the shaft, and means for securing said split nut against turning in the overhanging portion of said impeller.

5. In a shaft and hub securing means of the character described, the combination of a shaft having a shoulder extending therearound, a split externally threaded collar disposed upon said shaft in cooperating relation with said shoulder, a hub carrying member having an internally threaded portion at one end adapted to extend over said externally threaded split collar and another portion adapted to slidably engage said shaft, a keying means between the latter portion of said hub carrying member and said shaft, all whereby said hub carrying member may be adjusted axially along said shaft by a turning of said split collar within the internally threaded portion of said hub carrying member, and means for finally securing said split externally threaded collar against any turning within the internally threaded portion of said hub carrying member.

6. In a shaft and hub securing means of the character described, the combination of a shaft having a fixed shoulder forming means extending therearound, a split externally threaded collar disposed upon said shaft in cooperating relation with said shoulder forming means, a hub carrying member having an internally threaded portion at one end adapted to extend over said externally threaded split collar and another portion adapted to slidably engage said shaft, a keying means between the latter portion of said hub carrying member and said shaft, all whereby said hub carrying member may be adjusted axially with respect to the fixed shoulder forming means upon said shaft by a turning of said split collar within the internally threaded portion of said hub carrying member, and means for securing said split externally threaded collar against any turning after an adjustment of said hub carrying member upon said shaft.
